UNITED STATES PATENT OFFICE.

JOHN ZAGORODNY, OF HARTFORD, CONNECTICUT.

COMBINATION CLAPPER AND RATTLER.

Application filed October 22, 1925. Serial No. 64,162.

This invention relates to improvements in noise producing instruments for use during political campaigns or with parades etc., and more particularly to a combination clapper and rattler, and it is the principal object of the invention to provide an instrument of this kind of simple and inexpensive construction which can conveniently be handled and carried.

Another object of the invention is the provision of a clapper or rattler adapted to produce a rapid and sharp noise in short succession at each movement of the hammer in either direction.

A further object of the invention is the provision of a rattler combined with the hammer of the clapper to produce a rattling sound during the operation of the clapper in order to increase the noise made.

A still further object of the invention is the provision of a noise producing instrument of this type the clapper of which consists of two hemispherical members in which balls are loosely arranged to produce the sound, and which are adapted to be quickly and conveniently removed and attached to the instrument proper.

These and other objects and advantages of the invention will become more fully known as the description thereof proceeds, and will then be specifically defined in the appended claims.

In the accompanying drawing, forming a material part of this disclosure:

Fig. 1 is a side elevation of a combination rattler and clapper constructed according to the present invention, partly in section.

Fig. 2 is an end view of the same, partly in section.

The instrument constructed according to the present invention comprises a base board of resonant wood or other suitable material which may be called the soundboard and which in the drawing is designated 10, equipped with a handle 11 adapted to be conveniently gripped and held. A frame composed of two homogeneous elements or members 12 and 13 is secured with its foot flanges 14 and 15 respectively to the board 10 by means of suitable fastening means such as for instance the screws 16. The upper ends of the members 12 and 13 are bent to form shoulders and parallel, spaced sections or ears 17 and 18 between which the straight, parallel lower ends of a pair of parallel members 19 and 20 are pivotally attached by

means of a centrally located pin 21 having outer heads 22, 23. The members 19 and 20 above the ears 17 and 18 are shaped to form a loop 24, and are then formed into two parallel straight parts 25, 26 and their extreme outer ends are laterally rectangularly bent as at 27, 28 and then rectangularly vertically bent, as at 29, 30 to form cheeks between which the hammer or clapper 31 is held in place by means of screws 32, 33 or other suitable fastening means entering the sides of the hammer in approximately the center part thereof. The ends of the hammer 31 are tapered or beveled as at 34 to produce the sound producing faces 35.

A vibration strengthening spring or the like 36 having rectangularly bent ends 37 shorter than the hammer 31, are secured to the lower face of the hammer by means of screws 38 or the like, and their lateral middle sections are formed into loops 39 through which the parts 25, 26 are guided.

A transverse pin 40 is guided through members 12, 13 intermediate their ends and has outer threaded ends 41, 42 adapted to be screwed into threaded sockets 43, 44 centrally located on the inner faces or walls of two hemispherically shaped bell bodies 45, 46, while fastening nuts 47, 48 on the pin 40 engage the outer faces of members 12, 13.

Balls 49 and 50 are loosely guided within the two hemispherical bell bodies and adapted to freely move therein during the operation of the instrument.

The operation of the novel instrument will be entirely clear from the above description. If the handle is gripped by the hand of the operator below the sound board, and the instrument received an endwise movement up and down, the hammer will swing about its pivot pin 21 and alternately engage with its faces 35 the sound board to produce successive clapping sounds, while the balls within the hemispherical bell bodies will produce a rattling sound.

It will be understood that such changes may be made in the general arrangement and in the construction of the minor details of my novel instrument as shown and described as an example, as come within the scope of the appended claim without departure from the spirit of the invention.

Having thus described my invention, what I claim as new and desire to secure by Letters Patent is:

A combination clapper and rattler com-

prising a sound board of elongated shape, a handle for said board, secured at the lower face thereof, a pair of members having foot flanges for securing said members to the upper face of said board to form a frame thereon, ears formed at the upper end of said frame, a transverse pin in said members having threaded outer ends, a pair of hemispherically shaped bell-bodies, threaded 10 sockets on the inner faces of said bodies adapted to engage the threaded ends of said pin, means for holding the bell parts in relative positions, balls loosely held in said bell

bodies, a hammer having the lower end of its shaft pivotally attached to said members 15 adapted to swing about the same in endwise direction, a pair of sound faces at the ends of said hammer adapted to engage said board during the endwise up and down displacement of said board, and a vibratory 20 strengthening means attached to the lower face of said hammer.

Signed at Hartford in the county of Hartford and State of Connecticut, this 17th day of October A. D. 1925.

JOHN ZAGORODNY.
